UNITED STATES PATENT OFFICE.

JOHN ZURVALECZ, OF MARTIN, PENNSYLVANIA.

CHAIR-OPERATED FAN.

1,212,433.

Specification of Letters Patent. Patented Jan. 16, 1917.

Application filed September 13, 1915. Serial No. 50,426.

To all whom it may concern:

Be it known that I, JOHN ZURVALECZ, subject of the King of Hungary, residing at Martin, in the county of Fayette and State 5 of Pennsylvania, have invented certain new and useful Improvements in Chair-Operated Fans, of which the following is a specification.

This invention relates to certain new and 10 useful improvements in chair operated fans.

The primary object of the invention is the provision of a chair-carried fan adapted for automatic actuation during the rocking movement of the chair whereby the occupant 15 thereof may be fanned while being comfortably seated.

With this object in view and others that will appear as the nature of the invention is better understood, the same consists in the 20 novel combination and arrangement of parts hereinafter more fully described, illustrated in the accompanying drawings, and pointed out in the appended claim.

In the drawings forming a part of this 25 application and in which like designating characters refer to corresponding parts throughout the several views:—Figure 1 is a rear elevation of the device. Fig. 2 is a side elevation thereof. Fig. 3 is a view partially in side elevation but with the operating mechanism shown in vertical section, and Fig. 4 is an enlarged detail view partially in section of the operating mechanism of the device.

Referring more in detail to the drawings, it will be noted that the same broadly consists in a rocking chair 10 operatively positioned upon a base 11 an air circulating fan 12 being arranged for automatic actuation 30 during the rocking operation of the chair. The said base 11 is provided with a substantially H-shaped upright frame 13 rigidly secured thereto and having a segmental rack 14 pivotally attached as at 15 to one side thereof and extending through a slot 16 in the opposite side of the frame, the said rack being provided with a plurality of teeth 17 upon its lower curved edge.

A curved arm 18 is attached to the chair 50 back 19 and extends forwardly over the chair bottom 20 and is provided at its forward end with the said air circulating fan. The axle 22 of the said fan is journaled in the said end of the arm 18 and is provided with 55 a pulley wheel 23. A gear frame 24 is attached to the chair back 19 and has a stub

shaft 25 journaled therein and upon which shaft a gear 26 is secured which is in constant mesh with the rack teeth 17. The outer end of the shaft 25 is provided with a similar gear 27 which meshes with an idler 28 carried by the outer side 29 of the gear frame 24. Another shaft 30 is journaled in the frame 24 above the afore-mentioned shaft 25, while a grooved wheel 31 is secured to 60 the shaft 30 and fits over the upper edge of the rack 14.

A beveled pinion 32 is keyed to the outer end of the shaft 30 and has a hub 33 in the form of a gear which is in constant mesh 65 with the afore-mentioned idler 28.

An upright shaft 34 is journaled as at 35 to an upper corner of the gear frame 24 and is provided with a beveled pinion 36 in constant mesh with the afore-mentioned 70 pinion 32. A pulley 37 is attached to the upper end of the shaft 34, while a belt 38 passes over the two pulleys 37 and 23.

Normal positioning springs 39 connect the base 11 and front and rear portions of 80 the chair 10 for normally maintaining the chair with the bottom thereof horizontally positioned.

In operating the device, the occupant of 85 the chair being seated upon the chair bottom 20 rocks to-and-fro thereby longitudinally moving the rack 14 and the rack teeth 17 being in mesh with the gear 26 alternately turns the shaft 25 and by means of the gears 28 and 33 communicates motion to the pinions 32 and 36 for revolving the shaft 34 and pulley 37 alternately in different directions. The movement of the pulley 37 is communicated through the belt 38 to the pulley 23 and thus the air circulating fan 12 90 is alternately revolved in opposite directions thus agitating the air for the purpose of cooling the occupant of the chair.

While the form of the invention herein 100 shown and described is what is believed to be the preferred embodiment thereof, it is nevertheless to be understood that minor changes may be made without departing from the spirit and scope of the invention 105 as set forth in the claim.

What I claim as new is:—

A device of the type described, including a base, a rocking chair positioned upon said base, an upright frame secured upon said base, the rear member of which frame 110 has a slot near its upper end, a pivoted segmental rack upon said frame having a

toothed lower edge, said rack being received movably within said slot, a gear frame carried by the chair, a shaft journaled in said gear frame, a gear secured to said shaft 5 within said frame and in mesh with the teeth of said segment, a second shaft journaled in said gear frame, a sheave secured to said second shaft within the frame and receiving in its peripheral groove the upper 10 edge of said rack, a stub-shaft journaled in said gear frame and a gear mounted thereon outwardly of the frame, an outwardly positioned gear mounted on the first named shaft, in mesh with the last named gear,

a beveled gear mounted on said second 15 shaft, the hub of said beveled gear having peripheral teeth in engagement with the gear of the stub-shaft, an upright shaft journaled in said gear frame, a beveled gear carried by the upright shaft in engagement 20 with the last named beveled gear, a forwardly curved arm carried by the back of said chair, a fan journaled in the forward end of said arm, and operative connections between the fan and upright shaft. 25

In testimony whereof I affix my signature.

JOHN ZURVALECZ.

Copies of this patent may be obtained for five cents each, by addressing the "Commissioner of Patents, Washington, D. C."
